DRILL SHARPENER

Edward F. Wickens, Phillipsburg, N. J., assignor
to Ingersoll-Rand Company, New York, N. Y.,
a corporation of New Jersey

Application December 3, 1943, Serial No. 512,741

3 Claims. (Cl. 76—5)

This invention relates to forging machines, and more particularly to the type of forging machine known as drill sharpeners.

During a forging operation on machines of this type, much of the heat of the work-piece is usually transmitted throughout the machine and causes expansion of and often excessive wear on its movable parts and their bearings. A further objectionable feature in many machines of this type is that the valve mechanism controlling the supply of pressure fluid to the various portions of the machine is exposed to the atmosphere. Such valve mechanisms must, of necessity, be located conveniently to the operator's position which is, invariably at the side of the machine where the forging operation is being performed. Thus, in structures in which the valve mechanism is directly exposed to the atmosphere many of the scale particles flying from the work-piece lodge upon the valve and cause undue wear on the valve mechanism.

In accordance with the practice of the invention, it is contemplated to minimize the transmission of heat from the work to the bearing surfaces of the machine.

It is a further object to prevent excessive wear on the control valve mechanism of the machine. Other objects will be in part obvious and in part pointed out hereinafter.

In the drawing accompanying this specification and in which similar reference numerals refer to similar parts,

Figure 1 is a side elevation of a drill sharpening machine constructed in accordance with the practice of the invention.

Figure 2 is a similar view, partly broken away, showing the valve mechanism housed entirely within the main frame of the sharpener, and

Figure 3 is an end elevation, partly broken away, of the drill sharpening machine.

Referring more particularly to the drawing, the drill sharpener, designated in general by 20, comprises a main frame 21 and a crosshead 22 overlying the main frame.

The uppermost portion of the main frame 21 constitutes an anvil block 23, and in the opposed surfaces of the anvil block and the crosshead 22 are forming dies 24 and 25, respectively, that are suitably recessed to shape, for example, the cutting end of a drill steel 26. On the side of the frame 21 is a bracket 27 to support a percussive tool 28 serving to actuate a dolly 29 for forming the cutting teeth 30 on the drill steel 26.

Within the main frame 21 is a piston chamber 31 containing a piston 32 that is connected to

the crosshead 22 by a pair of columns 33 slidable vertically in the main frame. The columns 33 may, as is explained more fully in United States Patent No. 1,812,304 to A. E. Peters, extend with their lower portions below the piston 32 into guide cylinders 34 in the main frame to assist in guiding the reciprocatory elements of the sharpener.

Thus, as in the aforesaid patent, the lower ends of the column constitute pressure surfaces 35 that are subjected constantly to pressure fluid for raising the piston 32 and the parts connected thereto. Such pressure fluid is admitted into the guide cylinders 34 through ports 36 leading from a supply passage 37 in the lower portion of the main frame, and pressure fluid is conveyed to the supply passage 37 from a suitable source of expandible pressure fluid supply by a conduit 38 threadedly connected to the main frame.

The lower portion of the piston chamber 31 is in constant communication with the atmosphere through a port 39 opening into a discharge passage 40 in the main frame beneath the piston chamber 31 and an outlet 41 for the discharge passage. The upper portion of the piston chamber 31 constitutes a pressure chamber 42 into which pressure fluid is selectively introduced through an inlet passage 43 to act against the upper or actuating surface 44 of the piston 32 for effecting clamping movement thereof.

30 The inlet passage 43 serves to convey pressure fluid to the piston chamber and exhaust fluid therefrom. It opens axially into the piston chamber, and on the upper surface of the piston 32 is a projection 45 of slightly smaller diameter than the inlet passage 43 which it enters, as the piston 32 approaches the end of its upward stroke, to valve the fluid from the pressure chamber 42 at a sufficiently slow rate to prevent the sharp impact of the piston against the end wall of the piston chamber.

45 Preferably, a shallow annular recess 46 is formed in the upper end of the piston chamber around the inlet passage 43, wherewith it communicates, to assure the initial exposure of a suitable area of the actuating surface 44 to pressure fluid for starting the piston 32 on its downward or clamping stroke.

In the arrangement shown, the main frame is provided with a chamber 47 for pressure fluid and 50 a passage 48 in the main frame affords communication between the passage 37 and the chamber 47. The chamber 47 has an outlet passage 49 that leads to a valve mechanism 50 attached to the side of an interior wall 51 of the main 55 frame 21.

The valve mechanism 50 may be of a known type comprising a casing 52 having wings 53 that are clamped against the wall 51 by bolts 54. The casing 52 contains a sleeve 55 the interior of which serves as a valve chamber 56 that is in constant communication at its end with the space of chamber containing the valve mechanism 50, and in the intermediate portions of the sleeve and the casing are ports 57 and 58 that register, respectively, with the passages 49 and 43. The sleeve and the casing are further provided with ports 59 that communicate with a supply passage 60 extending through the main frame and the bracket 27 to the percussive tool 28.

The ports 57 are located between the ports 59 and 58 so that pressure fluid may be selectively valved from supply to either of the passages 60 and 43 or simultaneously to both, and in the sleeve 55 and the casing 52, below the ports 58, are exhaust ports 61 for the escape of fluid from the pressure chamber 42.

Within the valve chamber 56 is a reciprocatory valve 62 having an intermediate annular recess 63 and upper and lower end heads 64 and 65, respectively. The annular recess 63 is of such length that, in a given position of the valve, it will place both the ports 59 and 58 in communication with the ports 57 for actuating the piston 32 on its clamping stroke and to simultaneously operate the percussive tool 28.

The valve 62 is of the manually actuated type. It has a stem 66 at its upper end pivotally connected to a rocker 67 on a shaft 68 journaled in bearings 69 in the main frame 21. On an end of the shaft 68 projecting exteriorly of the main frame is a crank 70 for rocking the shaft to raise and lower the valve 62.

The space in the main frame 21 containing the valve mechanism constitutes an exhaust chamber 71 that is located between the piston chamber 31 and the anvil block 23 and communicates with the exhaust passage 40 through a passage 72. The exhaust chamber 71 extends upwardly to the anvil block portion 23 of the main frame which will, therefore, be exposed to the cooling influence of the fluid exhausted into the chamber 71 from the pressure chamber 42. In the side of the main frame 21 adjacent the valve mechanism 50 is an opening 73 to admit of access to the valve mechanism and said opening is normally sealed by a plate 74 secured to the main frame by bolts 75.

In the operation of the device, the piston 32 and the parts connected thereto are raised to their uppermost limiting positions by the pressure fluid acting against the surfaces 35 of the rods 33, and pressure fluid is selectively valved into the pressure chamber 42 for actuating the piston in the opposite direction. Thus, by placing the valve 62 in position to communicate the ports 58 and 59 with the port 57 pressure fluid will flow into the piston chamber 42 and move the piston 32 and the crosshead downwardly to clamp the work-piece between the dies. Pressure fluid will then also flow through the passage 60 to the percussive ele-

ment 28 for driving the dolly 29 against the work-piece.

Upon completion of the work, the valve 62 is moved downwardly to place the head 64 in position to seal the ports 57 and to effect communication between the ports 58 and 61 through the annular recess 63. The fluid in the piston chamber 42 will then pass through the ports 61 into the exhaust chamber 71, thence through the passages 72 and 40 to the atmosphere. In thus flowing through the exhaust chamber 71 the expanded fluid will carry away much of the heat transmitted to the anvil block by the work-piece and some of the oil entrained in the exhaust fluid entering the ends of the sleeve 55 from the chamber 71 will be deposited upon the wall of the valve chamber and effect the thorough lubrication of these important surfaces.

A further highly desirable feature of the present invention is that the valve mechanism lies in a dirt-free atmosphere and will, therefore, be well shielded from the dust and abrasive matter resulting from the forging operation. In consequence, these costly parts may operate for long periods of time without renewal and without necessitating frequent delays for the purpose of inspection and servicing.

I claim:

1. A drill sharpener, comprising a casing having a cylinder and an inlet chamber, there being an exhaust chamber above the cylinder, an anvil block on the casing above the exhaust chamber, a crosshead, a fluid actuated piston in the cylinder for effecting reciprocatory movement of the crosshead relatively to the anvil block, and valve means in one of the chambers for controlling the flow of expansible pressure fluid to and the exhaust of fluid from the cylinder and being housed entirely within and enclosed by the casing.

2. A drill sharpener, comprising a casing having a cylinder and inlet and exhaust chambers above the cylinder, an anvil block on the casing above the chambers, a crosshead, a fluid actuated piston in the cylinder to actuate the crosshead relatively to the anvil block, and valve means for controlling the flow of expansible pressure fluid to and the exhaust of such fluid from the cylinder and being located entirely within the exhaust chamber.

3. A drill sharpener, comprising a casing having a cylinder, an anvil block on the casing, a crosshead, a piston in the cylinder for effecting reciprocatory movement of the crosshead relatively to the anvil block, an exhaust chamber in the casing between the anvil block and the cylinder, and valve means for controlling the flow of expansible pressure fluid to the cylinder and the exhaust of fluid from the cylinder to the exhaust chamber located entirely within the exhaust chamber and having portions thereof exposed to the exhaust fluid and entrained oil in the exhaust chamber for oiling the valve mechanism.

EDWARD F. WICKENS.
